CANADA, A CORPORATION OF ONTARIO, CANADA

AUTOGRAPHIC REGISTER

Application filed March 30, 1922. Serial No. 547,986.

This invention relates to autographic registers and, with respect to its more specific features, to autographic registers adapted to utilize two or more superposed record strips or webs with manifolding accessories.

An object of the invention is to provide a convenient form of automatic register wherein in one of the duplicate webs is automatically filed.

Another object is to provide an efficient means for holding or retaining the blank web in place within the register casing.

Another object is to provide an improved means for tensioning the web or paper strip.

Another object is to provide an improved casing structure which is compact and has large capacity.

Another object is to provide an improved form of casing by which the various functioning parts are made accessible and easily manipulated.

Other objects will be in part obvious and in part pointed out hereinafter.

The invention accordingly consists in the features of construction, combination of elements and arrangement of parts which will be exemplified in the construction herein-after set forth, and the scope of their application will appear in the appended claims.

The drawings illustrate one embodiment of the invention and include—

Figure 1, a side elevation;

Fig. 2, a plan view;

Fig. 3, an end view;

Fig. 4, a cross-section showing the interior arrangement of the mechanism;

Fig. 5, a cross-section showing the means for feeding the strips or webs and aligning the same;

Fig. 6, a cross-section showing the manifolding means;

Fig. 7, detail view of a portion of the feed mechanism;

Figs. 8 and 9, a view of the feed mechanism in two conditions showing the method of aligning the webs;

Fig. 10, a cross-sectional detail view of the handle by which power is applied to the machine.

In the embodiment of the invention illustrated there is provided a casing which includes a base 1 upon which are supported a pair of side walls 2 braced apart by suitable rods 50; a rear wall 3 hinged upon the base 55 1 by means of suitable hinges 4; a platen 5 which provides a firm supporting surface for writing upon; and a top plate 6 hinged on a pair of pivotal screws 7 mounted on an extension 42 of platen 5. Rear wall 3 forms a 60 door to the rear of the casing and is provided with a suitable knob 17, and a spring catch 16 which co-operates with one of rods 50 to hold it closed. Extending forwardly from the base 1 and sloping upwardly therefrom is a 65 bottom wall 8 which supports a cover member 9 on hinges 10.

The wall 8 inclines upwardly at an angle less than 45 degrees whereby, as the strips are fed into the record compartment, they 70 are caused to resume their folded position because of the inclination of the wall, and at the same time, by reason of the fact that they are resting upon their face rather than upon their ends, they may be readily inspected. 75

Cover member 9 is formed preferably from a bent metal sheet and forms the front wall and the top of the forward part of the casing. Hinged-cover member 9 thus permits access to the forward part of the casing. Top plate 80 or wall 6 is provided with an aperture registering with platen 5, thereby leaving a rectangular space on the platen exposed.

The main portion of the casing is adapted for the reception of the strips or webs 51 and 52 which are to be fed over platen 5 where they are to be inscribed. In this main portion of the casing there are provided horizontal strips 11 attached to the inner side of side walls 2. These strips form slides to support suitable drawers 12. Drawers 12 are rectangular in plan and contain the webs 51 and 52. The webs are folded therein in zig-zag fashion to form pads or books. The pads so formed may fit closely in the draws and are held from lateral and endwise movement thereby. Sufficient space is left between the drawers to permit the webs to be unfolded and drawn therefrom at one end thereof. Drawers 12 are superposed one above the 100

other and are removable by sliding them on strips 11 and out through the rear end of the casing. They are prevented from moving too far forward by vertical strips 13 attached to the side walls 2 of the casing. When in position abutting strips 13, they are held against motion in the other direction by suitable bent spring members 14 mounted on side walls 2 to frictionally engage the sides of the drawers 12. Suitable handles 15 are provided for pulling the drawers from the casing. Adjoining the rear of drawers 12 there are provided rollers 18 transversely positioned across the casing. Rollers 18 serve as guides for the webs 51 as they are drawn from drawers 12 to the platen 5. In order to keep the webs 51 and 52 from frictionally interfering with each other there are provided guide rollers 19 positioned at the top of the casing and substantially in line with the platen 5. Each web, as it emerges from its drawer 12, passes over its respective guide rollers 18 and 19 to the surface of the platen, web 52 being positioned over web 51. They are prevented from being fed too fast by resilient spring members 20 which are attached to the outer wall of drawers 12. When the drawers are placed in operative position within the casing springs 20 are automatically set to press against the guide rollers 18, frictionally retarding the feed of the webs therebetween and producing tension therein beyond this point.

webs 51 and 52 are fed to the platen by a mechanism which comprises a shaft 21 rotatable in the casing and transversely supported thereby and upon which shaft is mounted a pair of discs 22 normally pressing against a roller 23. Shaft 21 carrying discs 22 is rotated by means of crank 24 mounted outside the casing, and carries a suitable handle 25. Motion is imparted to roller 23 by means of a gear 26 mounted on shaft 21 engaging with a pinion 27 mounted on roller 23. Roller 23 is mounted in a shield 29 pivotally mounted on the casing by means of screws 30. Spiral spring 31 press against the bearings of roller 23 and force said roller against discs 22. Shield 29 is held down so that roller 23 presses against discs 22, by a latch 32 mounted on a stud 55 on side wall 2 of the casing, and engaging a pin 33 mounted on shield 29. Backward rotation of shaft 21 is prevented by a pawl 34 engaging with a ratchet 35 on shaft 21.

Each web is provided with apertures spaced at suitable intervals longitudinally of the web and in alignment with the discs 22. Thus when shaft 21 is rotated the webs are gripped between discs 22 and roller 23 and advanced until the apertures in the webs register at the contacting point between the discs and the roller; there being no frictional engagement at this point, further advance is stopped. If the apertures in the various webs do not register with each other, that web whose

apertures arrive at the contacting point between discs 22 and roller 23 will stop advancing, while that web whose apertures have not yet reached this point will continue to advance until all apertures register. The forms on the webs should properly be printed so that they coincide when the apertures coincide.

In order to advance the webs beyond the position above described, there are provided lugs 28 which are supported by discs 22, and extend laterally beyond the perforations in the webs. Lugs 28 are flush with the circumference of discs 22; therefore when they come in contact with the webs they grip them to advance them to a point at which the discs 22 and roller 23 will again engage the body of the web, and thereupon further advancement of the webs is accomplished as before described.

Gear 26 is suitably encased in a cylindrical metal member 36 having a sheet metal cover 37. Cover 37 has an arm 38 extending radially therefrom, which engages with a pin 39 carried by crank 24. The purpose of this pin is to prevent rotation of the crank advancing the webs beyond position and condition for inscription at platen 5. Pin 39 may be withdrawn from engagement with the arm 38 by pulling the handle 25 laterally against the force of a spring 40 holding pin 39 in its normal engaging position. This operation is performed whenever it is desired to advance the web.

Manifolding of the writing on web 51 to web 52 is accomplished by carbon or other duplicating paper 41 deposited in a roll in a cavity formed by an extension 42 of the platen 5 located at one side of the casing. The carbon paper 41 passes between the webs 51 and 52 across platen 5 and under a metal strip 43 supported at a slight distance from the side wall 2 of the casing. Strip 43 holds the carbon paper against its tendency to be carried along by the webs.

After being fed between discs 22 and roller 23 the duplicate web 51 passes under a lip 54 and down into the forward portion of the casing and, due to its original folding and the slope of bottom wall 8 against which it is deposited, the web refolds in substantially its original form. The cover member 9 by virtue of its configuration helps to refold web 51 in its book form since the feeding of the strip forward into the record compartment causes it to strike the inclined outer face of the cover, and by reason of the inclination of that face, it is deflected downward toward the juncture of that face with the inclined wall 8, where it remains. When the next form is fed forward, it tends to buckle and its weakened line is carried by gravity to the lower edge of the inclined wall. Web 51 so deposited may be removed from the forward compartment of the casing upon swing-

ing back cover member 9. The folded pad of the used portion of web 51 discloses the forms thereon in the order of inscription.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

20 We claim:-

1. An autographic register including, in combination, means for containing a web and means adapted to tension said web as the latter is fed from said containing means, said tensioning means including a resilient member supported by said containing means and brought into resilient engagement with the web by the placing in operative position of said containing means.

2. An autographic register including, in combination, a drawer adapted to contain a web and means adapted to tension said web as the latter is fed from said drawer, said tensioning means including a spring member supported by said drawer and brought into resilient engagement with the web by the placing in operative position of said drawer.

3. An autographic register including, in combination, a casing, a drawer for each of a plurality of folded webs slidable within the casing and adapted to contain the web, said drawers being arranged in superposed relation within the casing and spaced from each other to permit the webs to be unfolded and drawn therefrom at one end thereof, and a spring web tensioning member on each said drawers movable to cooperate with and to tension the respective web as each drawer is moved into operative position.

50 In testimony whereof we affix our signatures.

LOUIS F. HAGEMANN.
WALTER GREIG.
